UNITED STATES PATENT OFFICE.

FREDERICK S. ANABLE, OF BROOKLINE, MASSACHUSETTS, ASSIGNOR TO NATIONAL BINDING MACHINE COMPANY, OF BOSTON, MASSACHUSETTS, A CORPORATION OF MAINE.

STRIP-SERVING DEVICE.

1,216,763.

Specification of Letters Patent. Patented Feb. 20, 1917.

Original application filed August 19, 1908, Serial No. 449,320. Divided and this application filed June 23, 1915. Serial No. 35,930.

To all whom it may concern:

Be it known that I, FREDERICK S. ANABLE, a citizen of the United States, and a resident of Brookline, in the county of Norfolk and 5 State of Massachusetts, have invented an Improvement in Strip-Serving Devices, of which the following description, in connection with the accompanying drawings, is a specification, like characters on the drawings 10 representing like parts.

This invention relates to devices or apparatus for supplying strips of paper or the like employed for wrapping or binding packages, or for use as labels of any desired 15 length, and has particular reference to that type of apparatus employing a support for a coil of paper strip previously gummed and then dried and having provisions for moistening the gum upon the strip as the latter 20 is drawn from its coil. It is apparent that an ungummed strip of paper or the like may be employed, in which case the moistening device for the strip suitably positioned with respect thereto would contain an adhesive in 25 stead of water.

This application is a division of my co-pending application for strip serving device, Serial No. 449,320, filed August 19, 1908, now Patent No. 1,147,290, July 20, 1915.

30 In order that the principle of the invention may be clearly understood, I have disclosed a single embodiment thereof in the accompanying drawing, wherein—

Figure 1 is a view in side elevation, partially in section, of the preferred form of 35 my invention;

Fig. 2 is a vertical section taken through the moistener shown in Fig. 1; and

Fig. 3 is a view similar to Fig. 2, but representing a slightly modified form of the invention.

I contemplate among other things the employment of means whereby the strip may be severed by strip pressure. This may be 45 accomplished in several ways, as, for example, by strip pressure upon the moistener, and herein I have represented a relatively movable moistener and severing means for effecting strip severance.

50 The strip support is represented at 1, it being of any suitable construction and being preferably a case wherein a roll of paper may be suitably supported and tensioned. Herein, it is represented as mounted upon

a base 2. Suitably secured to the said base 55 is a reservoir 3 mounted above the service path of the strip and provided with an inner wall 4, thus forming an inner chamber 5. Within the reservoir is mounted a block 6 having a central depending portion 7 adapted to be moved vertically in the chamber 5. Preferably the block 6 has depending portions 8 extending into the water of the reservoir. The said block is faced by a wicking 9, the ends whereof depend into the water 65 of the reservoir and the central portion whereof contacts with the strip. The depending portion 7 of the block 6 is suitably cut away to receive the fixed severing blade 10 suitably mounted in the support and in 70 such manner as to be normally shielded by the wicking.

The strip is drawn from the support in a substantially horizontal direction and the upper surface thereof is moistened by the 75 wick, which is, by the force of gravity, projected below the edge of the blade 10. When, however, a sufficient length of strip has been drawn from the support, the free end of the strip is moved upwardly, thus elevating the 80 block 6 and exposing the blade 10, so that the strip is severed. The free end of the strip then falls away from the moistener into a position where it may be readily grasped for further use. The strip is suitably guided in 85 its passage to the moistener, and herein for the purpose I have represented two rolls 11 and 12 located beneath the reservoir.

Instead of relying upon the weight of the block to project the moistener into moistening relation as represented in Figs. 1 and 2, I may employ a spring 13, as represented in Fig. 3, suitably connected if desired to the reservoir and block. The upper end of the spring may, if desired, be secured to the 90 upper face of the reservoir, and the lower end of the spring may, if desired, be secured to the lower end of the block, so that said block and moistener are spring supported. The spring 13 is of such strength that spring 100 pressure applied to the face of the moistener exposes the blade 10 for the severing operation.

While I have herein represented the wick or moistener and severing blade as above the 105 service path of the strip, it is obvious that I am not limited to such construction.

Having thus described one illustrative em-

bodiment of my invention, I desire it to be understood that although specific terms are employed, they are used in a generic and descriptive sense and not for purposes of limitation, the scope of the invention being set forth in the following claims.

Claims:

1. A strip serving device comprising a strip support, a moistener, a stationary severing device housed by the moistener, and means operated by strip pressure to bring the strip into severing relation with said severing device.
2. A strip serving device comprising a strip support and a moistener mounted for movement toward and from the service path of the strip, and a severing blade arranged within the area of the moistener.
3. A strip serving device comprising a strip support, a severing blade above the service path of the strip, and a moistener guarding said severing blade.
4. A strip serving device comprising a strip support, a stationary severing blade above the path of the strip, and a movable moistener above the service path of the strip adapted to house said blade during the moistening action but to expose said blade upon the application of strip pressure.
5. A strip serving device comprising a strip support, a severing blade, and a movable, gravity-impelled moistener mounted above the service path of the strip.
6. A strip serving device comprising a strip support, a moistener above the service path of the strip, and spring impelled toward said service path, and strip severing means inclosed by said moistener during non-use of the device.
7. A strip serving device comprising a strip support, a moistener, a severing device within the area of the moistener, and means

operated by strip pressure to bring the strip into severing relation with the severing device.

8. A strip serving device comprising a strip support, a moistener, and a severing blade mounted within the area of the moistener, said moistener and severing blade having a relative sliding movement to effect exposure of said severing blade for strip severance.

9. A strip serving device comprising a strip support, a moistener, and a severing blade mounted within the area of the moistener, the latter having a movement away from the edge of the severing blade when draft is imposed upon the strip.

10. A strip serving device comprising a strip support, a sliding moistener, and a stationary severing blade normally inclosed by said moistener, whereby the severing blade may be exposed for strip severance by draft upon the strip.

11. A strip serving device comprising a strip support, a moistener 9 and a severing blade 10 within the area of the moistener, said moistener and blade being relatively movable, whereby said blade may be exposed by draft upon the strip.

12. A strip serving device comprising a strip support 1, a moistener and a severing blade 10 arranged within the area of said moistener, said severing blade and moistener being relatively movable with respect to each other toward and from the service path of the strip.

In testimony whereof, I have signed my name to this specification, in the presence of two subscribing witnesses.

FREDERICK S. ANABLE.
